United States Patent Office

Des. 208,992
Patented Oct. 24, 1967

208,992

GARDEN CULTIVATOR

Howard A. Anderson, Pittsburgh, Pa., and Henry J. Rosendall, Grand Rapids, Mich., assignors to Bissell Inc., Grand Rapids, Mich., a corporation of Michigan

Filed Aug. 24, 1966, Ser. No. 3,574

Term of patent 14 years

(Cl. D35—2)

FIG. 1.

FIG. 2.

FIG. 3.

FIGURE 1 is a side elevation of a garden cultivator showing the new design, the opposite side being a mirror image;

FIG. 2 is a top plan view thereof; and

FIG. 3 is an end view thereof, taken on line 3—3 of FIGURE 1.

We claim:

The ornamental design for a garden cultivator, substantially as shown and described.
